UNITED STATES PATENT OFFICE

141,698

DESIGN FOR A DOLL WALKER OR THE LIKE

Herman Rapaport, Chicago, Ill.

Application March 8, 1945, Serial No. 118,348

Term of patent 3½ years

(Cl. D34—15)

To all whom it may concern:

Be it known that I, Herman Rapaport, a citizen of the United States, residing at Chicago, in the county of Cook and State of Illinois, have invented a new, original, and ornamental Design for a Doll Walker or the like, of which the following is a specification, reference being had to the accompanying drawing, forming part thereof.

Fig. 1 is a front perspective view of a doll walker or the like showing my new design.

Fig. 2 is a rear perspective view of same.

I claim:

The ornamental design for a doll walker or the like, as shown.

HERMAN RAPAPORT.
